UNITED STATES PATENT OFFICE.

GEORGE WASHINGTON MOORE, OF TULSA, OKLAHOMA.

WASHING-MACHINE.

1,168,096.

Specification of Letters Patent. Patented Jan. 11, 1916.

Application filed July 1, 1915. Serial No. 37,532.

To all whom it may concern:

Be it known that I, GEORGE W. MOORE, a citizen of the United States, residing at Tulsa, in the county of Tulsa and State of Oklahoma, have invented certain new and useful Improvements in Washing-Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in laundry apparatus and especially in the provision of a washer of the cylindrical type for use in laundries, etc., and consists of a simple and efficient device of this nature, having various details of construction, combination and arrangement of parts which will be hereinafter fully described, shown in the accompanying drawings and then specifically defined in the appended claim.

My invention is illustrated in the accompanying drawings, in which:

Figure 1 is a cross sectional view through a cylindrical washer. Fig. 2 is a sectional view on line 2—2 of Fig. 1. Fig. 3 is a detail sectional view showing a modified form of the washer. Fig. 4 is a detail view showing a still different modified form of the apparatus, and Fig. 5 is a detail perspective view of one of the slats.

Reference now being had to the details of the drawings by letter, A designates a cylinder to which a lid B is hinged and which is adapted to be rotated in any suitable manner, not shown. The inner surface of the cylinder is provided with a series of slats D, having angled wings D' which are bent toward each other, as shown in the sec-

tional view of the drawings, and terminate in rolls E, each of which is adapted to carry 45 a rod E'. The portions of the slats intermediate said wings have projecting parts D² which are fastened to the ends of the cylinder, the spaces between the ends of the slats being open in order to allow water to freely 50 enter the cylinder.

In operation, the clothes are placed inside the cylinder, the latter resting preferably in the water a suitable depth and, when the cylinder is rotated in either direction, continuously or alternating by reverse gears not shown, the slats will pick up the water, carrying it to the upper portion of the washer before it is poured back upon the clothes. The slats being spaced apart and properly shaped will pick up the water and carry it to the upper portion of the cylinder, thus causing a thorough agitation of the water by its being poured inside and outside through the clothes, the same time 65 that the clothes are agitated in the cylinder. This operation will force the suds through the clothes, thus thoroughly and quickly cleansing the same.

What I claim to be new is:

A cylindrical washer having a series of metallic slats secured to the inner circumferential surface thereof, each slat having oppositely disposed wings projecting from the edges thereof slight distances from the 75 ends, each wing being bent at right angles toward each other, forming a contracted passageway intermediate the angles, the outer ends of the wings terminating in rolls with contracted spaces between the rolls 80 upon adjacent slats.

In testimony whereof I hereunto affix my signature in presence of a witness.

GEORGE WASHINGTON MOORE.

Witness:

FLORENCE H. MOORE.
